FLY SWATTER

Adolph F. Shafter, Decatur, Ill., assignor to United States Manufacturing Corporation, Decatur, Ill., a corporation of Illinois

Application November 24, 1953, Serial No. 27,772

Term of patent 14 years

(Cl. D31—3)

To all whom it may concern:

Be it known that I, Adolph F. Shafter, residing in Decatur, county of Macon, and State of Illinois, have invented a new and original Design for a Fly Swatter, of which the following is a specification, reference being had to the accompanying drawing forming a part hereof, and in which:

Fig. 1 is a front elevational view of a fly swatter, showing my new design, a portion of the handle being broken away for purposes of illustration;

Fig. 2 is an edge elevational view thereof;

Fig. 3 is a top plan view thereof.

I claim:

The ornamental design for a fly swatter, as shown and described.
